UNITED STATES PATENT OFFICE.

STEPHEN A. RZATKIEWICZ, OF MILWAUKEE, WISCONSIN.

GATE LATCH.

1,418,174.

Specification of Letters Patent. Patented May 30, 1922.

Application filed August 4, 1921. Serial No. 489,768.

To all whom it may concern:

Be it known that I, STEPHEN A. RZATKIEWICZ, a citizen of the United States of America, residing at Milwaukee, in the county of Milwaukee and State of Wisconsin, have invented certain new and useful Improvements in Gate Latches, of which the following is a specification.

This invention relates to certain new and useful improvements in gate latches and has particular reference to a fence hook adapted positively to lock a gate in a closed position.

The primary object of the invention resides in the provision of a lock for gates wherein a hook that is resiliently mounted in a frame carried by the swinging end of a gate is adapted to engage an eye bolt for holding the gate in closed position with means associated with the hook to relieve the tension thereon and permit disengagement between the hook and eye bolt when the gate is to be opened.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view of a portion of a fence and a gate with the present form of gate lock operatively positioned thereon,

Figure 2 is a side elevational view, partly in section of the gate lock,

Figure 3 is an end elevational view of the gate lock, and

Figure 4 is a horizontal sectional view taken on line IV—IV of Fig. 2 showing the spring for holding the hook in locking engagement with the eye bolt and the pivotal connection between the hook and the supporting frame.

Referring more in detail to the accompanying drawing there is illustrated by the reference numeral 1, a portion of a fence having a gate frame 2 hinged thereto as at 3, the swinging end 4 of the gate carrying a locking device that cooperates with the adjacent post of the fence 1.

A gate locking device embodies a rectangular strap frame embodying spaced vertical side walls 5 and 6 and upper and lower

walls 7 and 8, the strap frame being bent from a single strip of material with the meeting ends 9 bent inwardly upon each other as shown in Figs. 2 and 4 for purposes presently to appear. A hook 10 having a bill 11 and an eye 12 at opposite ends has the eye received into openings 13 in the adjacent ends 9 of the strap frame, the hook securing the strap frame in its rectangular formation while the ends 9 of the frame constitute the support for the hook. An angle guard plate 14 is secured to the outer face of the side wall 5 of the frame and has an opening 15 in the outer end thereof for the reception of the extreme end of the bill 11, it being understood that the hook passes through a vertical slot 16 in the side 5 of the frame.

To hold the hook in its locked position, a coil spring 17 has its upper end 18 secured to opposite sides of the hook 10 as shown in Fig. 4, the lower end 19 of the spring being secured to an adjusting screw 20 that passes through an opening in the lower end 8 of the frame and is maintained in adjusted positions by the lock nuts 21, the nuts 21 controlling the face of the spring 17.

To elevate the hook to the dotted line position shown in Fig. 2, a chain 22 is attached to the hook and spring as shown in Figs. 1 and 2 and passes through an opening in the top wall 7 of the frame, and has secured to the upper end thereof a finger ring 23.

An eye bolt 24 is secured in the adjacent post of the gate fence 1 and is adapted to receive the bill 11 of the hook 10 and as shown in Figs. 1 and 2, the extreme end of the bill passing through the eye bolt 24 and entering the opening 15 under the guard plate will securely lock the gate in a closed position.

From the above detail description of the device it is thought that the construction and operation thereof will at once be apparent, it being noted that the inner end of the hook 10 secures the free end of the strap frames together while the ends of the strap frame constitute a removable support for the hook. The spring 17 will maintain the hook 10 under tension so that accidental disengagement of the hook from the eye bolt 24 will be prevented, the hook being disengaged from the eye bolt by elevating the same through the medium of the chain and finger ring as illustrated by dotted lines in Fig. 2. Also, the tension of the spring may be varied by the adjusting nuts 21, thereby

permitting a variance in the tension of the locking hook.

While there is herein shown and described the preferred embodiment of the present invention, it is nevertheless to be understood that minor changes may be made therein without departing from the spirit and scope thereof as claimed.

What is claimed as new is:—

- 10 1. A gate lock comprising a frame formed
of a strap bent into rectangular formation
with the adjacent ends of the strap directed
inwardly, a hook pivoted to the adjacent
ends of the strap and having the bill end
15 thereof projecting through the opposite side
of the frame strap, a spring extending be-
tween said hook and the bottom of the
frame, a guard plate secured to the outer
side of the frame and having an opening
20 therein to receive the extreme end of the
hook bill, and an eye bolt receiving said
hook at a point above the guard plate.

25 2. A gate lock comprising a frame formed
of a strap bent into rectangular formation
with the adjacent ends of the strap directed
inwardly, a hook pivoted to the adjacent
ends of the strap and having the bill end
thereof projecting through the opposite side
30 of the frame strap, a spring extending be-
tween said hook and the bottom of the
frame, a guard plate secured to the outer
side of the frame and having an opening
35 therein to receive the extreme end of the
hook bill, an eye bolt receiving said hook at
a point above the guard plate, and means for
elevating the hook against the tension of the
spring.

40 3. A gate lock comprising a frame formed
of a strap bent into rectangular formation

3. A gate lock comprising a frame formed of a strap bent into rectangular formation

with the adjacent ends of the strap directed 40 inwardly, a hook pivoted to the adjacent ends of the strap and having the bill end thereof projecting through the opposite side of the frame strap, a spring extending between said hook and the bottom of the 45 frame, a guard plate secured to the outer side of the frame and having an opening therein to receive the extreme end of the hook bill, an eye bolt receiving said hook at a point above the guard plate, a chain secured at its lower end to said hook and spring, and a ring attached to the upper end of the chain and overlying said frame adapted to release the hook from engagement with the eye bolt. 50 55

4. A gate lock comprising a frame formed of a strap bent into rectangular formation with the adjacent ends of the strap directed inwardly, a hook pivoted to the adjacent ends of the strap and having the bill end thereof projecting through the opposite side of the frame strap, a spring extending between said hook and the bottom of the frame, a guard plate secured to the outer side of the frame and having an opening therein to receive the extreme end of the hook bill, an eye bolt receiving said hook at a point above the guard plate, a chain secured at its lower end to said hook and spring, a ring attached to the upper end of the chain and overlying said frame adapted to release the hook from engagement with the eye bolt, and cooperating devices carried by the lower end of the spring and the frame for varying the tension of the spring. 75

In testimony whereof I affix my signature.

STEPHEN A. RZATKIEWICZ.
